UNITED STATES PATENT OFFICE.

ERNEST F. PFLUEGER, OF AKRON, OHIO.

HARNESS-PAD.

SPECIFICATION forming part of Letters Patent No. 399,074, dated March 5, 1889.

Application filed October 31, 1888. Serial No. 289,600. (No model.)

To all whom it may concern:

Be it known that I, ERNEST F. PFLUEGER, a citizen of the United States, and a resident of Akron, in the county of Summit and State 5 of Ohio, have invented certain new and useful Improvements in Medicated Sweat-Pads; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a representation of this invention, and shows the under side of the pad. Fig. 2 is a plan view of one-half of the pad, and shows the healing-substances spread upon the inside. Fig. 3 is a 20 section across the pad.

This invention has relation to sweat-pads for healing sore necks of horses; and it consists in the construction and novel combination of parts, all as hereinafter set forth, and 25 pointed out in the claim appended.

In the accompanying drawings, the letter A designates the pad, which is of the ordinary elongated form, and is made of strong cloth, through the meshes of which the medicated 30 compound inclosed may act. The sweat-pad is made in a bag form and the compound is placed inside and spread out in a flattened layer, so that two sides of the pad may approximate each other. The pad is then 35 stitched or quilted, as indicated at *b b*, so that it will be held in place within it. The medicated compound or filling consists of ground

cork, sulphate of zinc, acetate of lead, carbolic acid, salicylic acid, and starch. The cork in this ground form serves to hold the medicinal 40 ingredients, and will absorb the perspiration when in use without caking or hardening. It forms a light and elastic pad well adapted for the purpose in view.

To the inner surface of the sweat-pad, or to 45 that surface which is applied to the neck or the shoulder of the animal, I design to secure a section of cloth to which has been applied some healing solution—such as the sulphate of zinc or acetate of lead—or the cloth of the 50 pad itself may be treated with such a solution. I prefer, however, to use an additional section of cloth, in order that it may be replaced when worn or exhausted. It will thus serve as a re-enforcement or guard to the cloth of the 55 pad itself.

Having described this invention, what I claim, and desire to secure by Letters Patent, is—

The medicated sack-pad for harness, con- 60 sisting of the medicated cloth sides and an intermediate flattened layer of ground cork and astringent chemicals with starch and car- bolic acid, said sides being held together by edge stitches and by quilting-seams through 65 said intermediate layer, substantially as speci- fied.

In testimony whereof I affix my signature in presence of two witnesses.

ERNEST F. PFLUEGER.
